UNITED STATES PATENT OFFICE.

LUCAS A. BARTELS, OF HARTFORD, CONNECTICUT.

ADJUSTING MEANS FOR SPRING SCREW-THREADING DIES AND HOLLOW MILLS.

1,164,567.

Specification of Letters Patent. Patented Dec. 14, 1915.

Application filed November 19, 1912. Serial No. 732,304.

To all whom it may concern:

Be it known that I, LUCAS A. BARTELS, a citizen of the United States, residing at Hartford, in the county of Hartford and 5 State of Connecticut, have invented new and useful Improvements in Adjusting Means for Spring Screw-THREADING DIES and Hollow Mills, of which the following is a specification.

10 The invention relates generally to an improvement in spring screw threading dies and hollow mills, and particularly to a means for adjusting such parts in a simple and accurate manner.

15 The main object of the invention resides in the production of a ring arranged for threaded engagement with the threading die or hollow mill, and which through the peculiar formation of the threaded surfaces 20 of the die or mill and ring, will adjust such die or mill.

25 The invention will be described in the following specification, reference being had particularly to the accompanying drawing,

30 in which:

Figure 1 is a view in elevation partly in section illustrating the improvement as applied to a spring screw threading die. Fig. 2 is a sectional view of the ring. Fig. 3 is 35 a view similar to Fig. 1 showing the invention applied to a hollow mill. Fig. 4 is a detail sectional view illustrating the manner of engagement of the prongs with the adjusting ring.

40 In the details of improvement the threading die or hollow mill, as the case may be, is exteriorly threaded at 1 and such threading is peculiar in that the depth of each succeeding thread from the operative end 45 of the die or mill toward the opposite end is of reduced depth, as viewed in section, or in other words the threading channel on the die or mill has its maximum depth at the initial or entrant end, and is gradually and uniformly reduced in depth therefrom toward the opposite end.

45 The adjusting ring 2, which is interiorly of a size to coöperate with the die or mill is 50 interiorly threaded at 3, said threads having a pitch to engage with the threads on

the die or mill but the threaded surface of the ring is tapered with the larger end of a size to exactly coöperate with the initial thread channel on the die or mill without compression of the parts.

55 In use the ring is threaded upon the die or mill to accomplish a desired adjustment it being noted that the gradual reduction in the depth of the threaded channel of the die or mill together with the tapered arrangement of the threaded portion within the ring insures such movement of the prongs or lands as will provide for the desired adjustment.

60 The improvement is of material advantage over other adjusting means heretofore provided in that it insures an absolutely uniform movement of the lands in the adjusting operation, so that when adjusted the work of the lands will be evenly distributed between all of them and no one 65 will wear more than another. Furthermore the uniform movement of all lands in the adjustment prevents threading off center and thereby insures more perfect work. 70 The ring may be readily and conveniently applied and in use will even tend to correct irregularity in the position of the lands incident to there having to come out of shape during the hardening process. The 75 ring may be formed exteriorly in any way to provide for its ready operation in applying it to or removing it from the die or mill.

Having thus described the invention, 85 what I claim as new, is:—

A cutting implement having prongs and formed with an adjusting thread channel, said channel being of gradually decreasing depth from the entrant end, and a ring arranged for threaded connection with said channel, said ring being interiorly threaded throughout a tapered surface.

90 In testimony whereof I affix my signature in presence of two witnesses.

LUCAS A. BARTELS.
